DRIVER MEANS FOR MAGNETIC ELEMENTS

Ernest J. Schubert, Berwyn, Pa., assignor to Westinghouse Electric Corporation, East Pittsburgh, Pa., a corporation of Pennsylvania

Application December 20, 1957, Serial No. 704,100

8 Claims. (Cl. 307—88)

This invention relates to driver means for magnetic elements, and more particularly, to a transistor drive for a plurality of magnetic elements.

It is presently a practice to provide separate transistor drive means for magnetic elements for the purpose of maintaining the transistor load within the rating. In some cases, it has been found to be satisfactory to drive a plurality of magnetic cores from a single transistor where a constant current supply can be provided. However, constant current drive for transistors is impractical in many cases because of the voltages involved in the operation of the transistor.

It is therefore an object of this invention to provide a circuit arrangement capable of allowing a plurality of magnetic elements to be driven from a single transistor without the necessity of a constant current source.

It is another object of this invention to provide a transistor drive for a plurality of magnetic elements provided with a feedback circuit capable of maintaining the transistor drive for the total switching period of the cores even though the triggering impulses to the transistor may be of very short duration.

It is another object of this invention to provide a constant load circuit for a transistor drive for magnetic elements during changing outputs.

Other objects, processes and characteristic features will become obvious as the description of the invention progresses.

In practicing this invention, the circuit arrangement is formed around magnetic element applications, such as ring counters, complement-registers and selector switches where the total number of cores containing One's and those containing Zero's is equal and constant. In this type of circuit the transistor output can be coupled to as many as 24 cores for providing drive voltages for the cores with the cores being arranged in parallel branches in which at least a Zero and a One is positioned in each branch. The cores are then provided with a feedback circuit either parallel or series arranged to provide sufficient current during a sufficient time duration to maintain the transistor in conduction for a time period sufficient to allow the cores to be driven from one saturation to the other.

Figure 1 shows a transistor drive for magnetic cores involving the use of a series feedback circuit.

Fig. 2 is a diagrammatic showing of a transistor having a plurality of parallel output paths for driving magnetic cores in which a parallel feedback circuit is used.

In each of the several views, similar parts bear like reference characters.

The driver circuit of Fig. 1 utilizes a transistor 1 having an emitter 2, a collector 3 and a base 4. The transistor 1 is connected to a trigger source to apply a control impulse to the base 4 through a diode 5 for assuring proper decoupling of the trigger source from the feedback loop. The collector 3 of the transistor 1 is provided with parallel circuits having input windings 6, 7, 8 and 9 positioned on the saturable cores A, B, C

and D, respectively. The input windings 6 and 7 are placed in series and connected to the collector 3 through a conductor and to a negative terminal B— of a source of power such as a battery, not shown, having center terminal N grounded. Similarly, the input windings 8 and 9 are connected in series and between the collector 3 and the negative terminal B— of the source of power. In order to provide a balanced load circuit for the transistor 1, it is necessary that the pair of cores A, B and the pair C, D, respectively, are set in opposite states prior to the operation of the transistor so that only one of the pair of cores A, B or C, D will be in the state One. This arrangement is accomplished through the use of the control windings 12 and 11 mounted on the cores A and B, respectively, and wound in opposite sense so that a voltage of one polarity being applied against the cores in series would cause the insertion of a One in one core and of a Zero in the other core.

The control windings 12 and 11 may be connected to any source i.e., a control circuit having parallel control paths between B+ and ground, and B— and ground where ground is the center tap point on the battery. The parallel paths may be arranged through the switches 13 and 14 controlled by a control element such as recorder control 15 in such a manner that only one of the parallel paths can be completed at any one time. For example, when the switch 13 is shown in one of its extreme positions, such as shown in the drawing of Fig. 1, a path is complete from B— through the contact member 13b of the switch 13 through the control windings 12 and 11 connected in series to the ground point end with the switch 13. In this position, the contact member 13a acts to interrupt the path from the plus terminal of the source of power through the contact member 14 and windings 12 and 11 connected in series to ground. Even though the contact member 14 may be closed, the switch member 13a would maintain the circuit in an interrupted condition. If the switch 13 was reversed, it can be seen that the path from B— to N through the input windings 12 and 11 would become interrupted and the path from B+ to N through the control windings 12 and 11 would be prepared for completion upon the operation of the switch 14. It is therefore possible to insert information in the core A and the complement into B by means of the windings 12 and 11.

In order to insure that the control impulses delivered to the transistor 1 over its trigger circuit connected to the base 4 are independent from the switching time of the cores A and B, a feedback circuit comprising the windings 16 and 17 placed about the cores A and B, respectively, is provided. The windings 16 and 17 are connected in the circuit originating at ground passing through a pair of windings 18 and 19, to be explained hereinafter, on the cores C and D. The windings 16 and 17 are connected in series and a diode 20 assuring proper decoupling is maintaining transistor conduction during this period to the base 4 of the transistor. With this circuit, it can be seen that any negative E.M.F. induced in the cores A and B would be delivered through the diode 20 to the base member 4 of the transistor 1. The magnetic cores A and B are provided with output coils 21 and 22, respectively, on the output lines 23 and 23a, respectively, for delivering output impulses to be utilized in any desirable manner.

When a pulse or binary input is applied to the transistor 1 it will be fed to the input windings 6 and 7. This can result in an output on conductor 23 or conductor 23a. The output is selectively fed through one of these conductors depending upon the position of switches 13 and 14 which are actuated by the recorder control 15. The output of transistor 1 is also applied to input windings 8 and 9 which can similarly result in an output on

conductor 30 or conductor 30a depending on the position of switches 26 and 27. As explained before, the windings 8 and 9 of the cores C and D are connected in parallel with the input windings 6 and 7 of the cores A and B and are therefore energized at the same moment as the windings 6 and 7. The cores C and D are also provided with control windings 24 and 25 which are similar to the control windings 12 and 11 of the cores A and B. The windings 24 and 25 are also controlled over parallel circuits including the positive and negative terminals of the battery to the neutral terminal N of the battery with the circuits being completed over a switch 26 having contacts 26a and 26b in the positive and negative branches of the parallel circuit, respectively, and operable in a manner identical with the operation of the switch 13 described hereinafter. The circuit including the positive terminal B+ of the battery to the center terminal battery N also includes a control switch 27 controlled over a control mechanism such as the control mechanism 15 indicated above to provide the proper output response desired. The cores C and D are thus explained in a manner similar to the core A and B with only one of the cores set to One at a time. It can be seen, therefore, that additional parallel paths such as this can be provided to the maximum load limit of the transistor 1 as well as each parallel path connected to the collector 3 of the transistor 1 includes equal number of magnetic cores containing One's and Zero's.

It is pointed out that the cores C and D are also provided with output windings 28 and 29, respectively, on the output conductors 30 and 30a, respectively, for delivering output impulses to be used in any desired manner. The cores C and D are also provided with feedback windings 18 and 19 previously mentioned as connected in series with the feedback windings 16 and 17 of the cores A and B. Voltage of proper polarity picked up by any one of the windings 16 through 19 would therefore provide adequate feedback energy to maintain the transistor 1 in conduction for a period sufficiently long to allow the cores A and B or C and D to complete their switching.

The driver circuit shown in Fig. 2 is identical with the circuit shown in Fig. 1 with the exception that the feedback circuit for the cores A and B and C and D include parallel connected circuits rather than a series connected circuit as shown in Fig. 1. For example, the windings 16 and 17 of the cores A and B are connected in parallel with the windings 18 and 19 of the cores C and D with the junction provided between windings 16 and 17 being polarized by the diode 31 and the junction of the windings 18 and 19 being polarized by the diode 32 with the two circuits connected in parallel to the conductor 33 which is in turn connected to the base member 4 of the transistor 1. It can be seen that in this case also, energy delivered to any one of the windings 16 through 19 is placed on the base member 4 of the transistor 1 and is utilized to maintain conduction of the transistor until the core functions are completed.

Since numerous changes may be made in the above-described construction, and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. A driver circuit for magnetic elements comprising a transistor having emitter, collector and base electrodes, a plurality of saturable magnetic elements each having input and control windings, said input windings being connected in series and to said collector, said control windings being positioned on said elements so that energy of one polarity only drives one-half of the said plurality of magnetic elements to one saturation and energy of

the opposite polarity drives the other half of said magnetic elements to saturation, and feedback means for maintaining said transistor in conduction state following a trigger pulse of short duration on said base.

5 2. A driver circuit for magnetic elements comprising a transistor having emitter, collector and base electrodes, a plurality of saturable magnetic elements each having input and control windings, said input windings being connected in series and to said collector, said control windings being positioned on said elements so that energy of one polarity only drives one-half of the said plurality of magnetic elements to one saturation and energy of the opposite polarity drives the other half of said magnetic elements to saturation, and feedback means for maintaining said transistor in conduction state following a trigger pulse of short duration on said base, said feedback means comprising windings on said magnetic elements.

10 3. A driver circuit for magnetic elements comprising a transistor having emitter, collector and base electrodes, a plurality of saturable magnetic elements each having input and control windings, said input windings being connected in series and to said collector, said control windings being positioned on said elements so that energy of one polarity only drives one-half of the said plurality of magnetic elements to one saturation and energy of the opposite polarity drives the other half of said magnetic elements to saturation, and feedback means for maintaining said transistor in conduction state following a trigger pulse of short duration on said base, said feedback means comprising windings on said magnetic elements.

15 4. A circuit for magnetic cores comprising a transistor having emitter, collector and base electrodes, a plurality of saturable magnetic cores, each having input and control windings, said input windings being connected in a plurality of series paths connected in parallel to said collector, said control windings being positioned on said cores so that energy of one polarity only drives one-half of the cores of the series connected input windings of each parallel path to saturation and energy of the opposite polarity drives the remaining cores to saturation.

20 5. A circuit for magnetic cores comprising a transistor having emitter, collector and base electrodes, a plurality of saturable magnetic cores, each having input and control windings, said input windings being connected in a plurality of series paths connected in parallel to said collector, said control windings being positioned on said cores so that energy of one polarity only drives one-half of the cores of the series connected input windings of each parallel path to saturation and energy of the opposite polarity drives the remaining cores to saturation, and feedback means for maintaining said transistor in conduction following initial conduction by an input pulse on said base.

25 6. A circuit for magnetic cores comprising a transistor having emitter, collector and base electrodes, a plurality of saturable magnetic cores, each having input and control windings, said input windings being connected in a plurality of series paths connected in parallel to said collector, said control windings being positioned on said cores so that energy of one polarity only drives one-half of the cores of the series connected input windings of each parallel path to saturation and energy of the opposite polarity drives the remaining cores to saturation, and feedback means for maintaining said transistor in conduction following initial conduction by an input pulse on said base, said feedback means comprising windings on said cores.

30 7. A circuit for magnetic cores comprising a transistor having emitter, collector and base electrodes, a plurality of saturable magnetic cores, each having input and control windings, said input windings being connected in a plurality of series paths connected in parallel to

said collector, said control windings being positioned on said cores so that energy of one polarity only drives one-half of the cores of the series connected input windings of each parallel path to saturation and energy of the opposite polarity drives the remaining cores to saturation, and feedback means for maintaining said transistor in conduction following initial conduction by an input pulse on said base, said feedback means comprising windings on said cores, said windings being connected in series.

8. A circuit for magnetic cores comprising a transistor having emitter, collector and base electrodes, a plurality of saturable magnetic cores, each having input and control windings, said input windings being connected in a plurality of series paths connected in parallel to said collector, said control windings being positioned

on said cores so that energy of one polarity only drives one-half of the cores of the series connected input windings of each parallel path to saturation and energy of the opposite polarity drives the remaining cores to saturation, and feedback means for maintaining said transistor in conduction following initial conduction by an input pulse on said base, said feedback means comprising windings on said cores, said windings being connected in series parallel arrangement.
